(57) **CLAIM**

The ornamental design for a ceiling fan with light, as shown and described.

DESCRIPTION

FIG. 1 is a front, top perspective view of a ceiling fan with light, showing my new design;

FIG. 2 is a rear, bottom perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof; and,

FIG. 9 is an enlarged view of the area labeled 9 in FIG.1. The broken lines show portions of the ceiling fan with light that form no part of the claimed design.

The dashed lines in the figures illustrate portions of the ceiling fan with light that form no part of the claimed design. The dot-dash broken lines of the ceiling fan with light in FIG. 1 illustrate a boundary and cut line of the enlarged view in FIG. 9 and form no part of the claimed design.
